UNITED STATES PATENT OFFICE.

HENRY FISHERING, OF CINCINNATI, OHIO.

PIPE-CLAMP.

SPECIFICATION forming part of Letters Patent No. 762,994, dated June 21, 1904.

Application filed February 1, 1904. Serial No. 191,432. (No model.)

To all whom it may concern:

Be it known that I, HENRY FISHERING, a citizen of the United States of America, and a resident of Cincinnati, county of Hamilton, 5 State of Ohio, have invented certain new and useful Improvements in Pipe-Clamps, of which the following is a specification.

The object of my invention is a clamp for holding a pipe securely while it is being operated upon without marring its surface.

A further object is to provide a combination pipe clamp and wrench.

These objects are obtained by the means illustrated in the accompanying drawings, in 15 which—

Figure 1 is a plan view of a pipe-clamp embodying my invention, showing it with a pipe clamped in position. Fig. 2 is a side elevation of the same, the full line showing the 20 jaws interlocked and held in place, dotted lines showing the same before they have been interlocked. Fig. 3 is an end view looking from the left of Fig. 1. Fig. 4 is an end view looking from the right of Fig. 1. Fig. 5 is a central 25 sectional view taken upon lines X X of Fig. 1. Fig. 6 is a perspective view of the same.

Referring to the parts, the upper jaw A of the clamp has downwardly-projecting wedge-shaped teeth a and a' and wedge-shaped faces a^2 and a^3 , whose wedges are parallel to those of the teeth a and a' . Lower jaw B has upwardly-projecting wedge-shaped teeth b and b' , corresponding to teeth a and a' , to engage faces a^2 and a^3 , and wedge-shaped faces b^2 and b^3 , corresponding with faces a^2 and a^3 , to be engaged by teeth a and a' . Journaled upon pins C and C' in jaw A are two swinging arms c and c', between whose forward ends is journaled a roller having eccentricities c^2 and c^3 . The front edge of teeth b and b' are beveled off to engage the eccentricities, so that when the roller is rotated, which may be done by engaging nut c^4 by a wrench, the jaw A is drawn forward upon jaw B, and the 40 wedges therefore clamp the jaws tightly together. Jaw A and jaw B each has a longitudinal semicircular groove a^4 and b^4 , which register with each other when the jaws are engaged together. Each of these grooves 45 seat a semicircular bushing D and D', which together form a seat for the reception of the

pipe E, which is to be operated upon. These bushings are made removable, so that different-sized bushings may be used to vary the size of the seat for use with different-sized 55 pipes. To facilitate the removal or replacement of these bushings, jaws A and B have longitudinal radial grooves a^5 , a^6 , b^5 , and b^6 formed in them, and the bushings have corresponding radial ridges d upon their circumference 60 to engage the grooves, so that one bushing may be readily drawn out of the jaw and another one inserted in its place.

In order to secure the clamp in place while operating upon the pipe, jaw B has two longitudinal notches b^7 b^8 formed near its lower edge, which engage flanges f f' of ways G, 65 which are secured to the table.

The exterior of the clamp is made angularly, so that the same will form a firm seat 70 for a wrench.

In operation a pipe E to be operated upon is inserted between the jaws A and B while they are loose. Then the arms c and c' are swung forward and the eccentricities are rotated 75 by means of a wrench engaging the nut c^4 , which operation draws the jaws down firmly upon the pipe E. The operation, as hereinbefore described, may be performed either before the clamp is placed in the way F or 80 afterward. Then the operation of screw-threading or of otherwise operating upon the pipe is performed. Now should it be desired to insert the pipe in place in a machine—as, for instance, a water-heater—or to fit it in 85 place in the water system of a house the clamp is left locked together and is removed from the ways F. The jaws then form a convenient seat for a wrench to fit the pipe in place, after which by loosening up eccentricities c^2 and c^3 the clamp may be removed 90 readily from the pipe.

I have shown my invention in the best form known to me; but it is obvious that many mere mechanical changes might be made 95 therein without departing from the spirit or scope of my invention.

What I claim is—

1. In a pipe-clamp the combination of two jaws having interlocking wedge-shaped faces, 100 each having a groove registering with a groove in the other and forming therewith a pipe-

seat, and an eccentric journaled upon one of the jaws to engage a seat upon the other and to draw the jaws together substantially as shown and described.

5. 2. In a pipe-clamp the combination of two jaws having interlocking wedge-shaped faces and each having a longitudinal groove to register with one in the other to form a pipe-seat, arms journaled upon one of the jaws, an eccentric carried rotatively by the arms to engage the other jaw to draw the two firmly together substantially as shown and described.
- 10

3. A pipe-clamp consisting of two interlocking jaws formed angularly upon their exterior and having longitudinal grooves to form 15 a pipe-seat, means for locking the jaws together, and a fixed way to be removably engaged by the jaws substantially as shown and described.

HENRY FISHERING.
